UNITED STATES PATENT OFFICE

98,005

DESIGN FOR A GAME PIN OR SIMILAR ARTICLE

Harry F. Kohaut, East Orange, N. J.

Application September 19, 1935, Serial No. 58,621

Term of patent 3½ years

To all whom it may concern:

Be it known that I, Harry F. Kohaut, a citizen of the United States, residing in the city of East Orange, in the county of Essex and State of New Jersey, have invented a new, original, and ornamental Design for a Game Pin or Similar Article, of which the following is a specification, reference being had to the accompanying drawing, forming a part thereof.

In the drawing,

Fig. 1 is a front elevational view of a game pin embodying my design and

Fig. 2 is a side elevational view thereof.

I claim:

The ornamental design for a game pin or similar article, as shown.

HARRY F. KOHAUT.
